UNITED STATES PATENT OFFICE.

JOSEPH H. AUSTIN AND BERT W. GINN, OF RICHMOND, VIRGINIA, ASSIGNORS TO THE AMERICAN TOBACCO COMPANY, OF NEW YORK, N. Y., A CORPORATION OF NEW JERSEY.

MACHINE AND PROCESS FOR BLENDING AND STRIPPING TOBACCO.

Application filed September 29, 1924, Serial No. 740,561. Renewed November 12, 1925.

This invention is an improvement in method and apparatus for stripping tobacco, and with respect to its more specific features, in methods and apparatus for blending and 5 stripping.

One of the problems in the handling of tobacco most difficult of solution, is the stripping of the leaf lamina from the stem. It is desirable that as large a proportion as possible of the lamina be retained, with as small a proportion as possible of the woody stems, in order that all of the valuable portion be utilized.

In the methods at present practiced, the 15 lamina is stripped from the main stem while the stem is grasped in some portion of its length to make counter resistance, or the leaf is subjected to the action of disintegrators or thrashers, which break up, and afterwards screen the lighter portions from the 20 heavier.

Neither method is entirely satisfactory. In neither is the separation complete, a large 25 portion of the valuable lamina remaining with the stem. In the former method the process is slow and expensive, requiring as it does, individual treatment of the leaves, and in the latter, the separated lamina contains a large proportion of the undesirable 30 woody stem. Furthermore, an appreciable amount of the lamina in the form of finer particles is lost in the process of separation.

An object of the present invention is to provide a method of complete separation of 35 lamina and leaf, adapted to operate upon the leaf in mass, with a minimum of manual manipulation.

Another object is to provide a method 40 which includes blending of the tobacco prior to the separation of the lamina and stem in any selected combination of grades.

Another object is the provision of a new 45 and improved apparatus for carrying out the method in a simple and efficacious manner.

Another object is to provide in connection 50 with the apparatus, means for recovering from the air blast used in the separation, a large amount of fine particles, usually lost.

With these and other objects in view, the 55 invention consists in the method and the

several steps thereof, and in the construction and novel combination of parts fully described hereinafter, illustrated in the accompanying drawings, and pointed out in the claims appended hereto, it being understood 55 that various changes in the form, proportion, size and minor details of construction, within the scope of the claims, may be resorted to without departing from the spirit of the invention.

In the drawings:

Fig. 1 is a section through three floors, showing a layout of the apparatus, and with the apparatus in side elevation, and somewhat diagrammatically shown.

Fig. 2 is a plan view of the layout of the two upper floors.

Fig. 3 is a vertical longitudinal section of the first of the thrasher machines.

Figs. 4 and 5 are similar views of parts of 70 the intermediate machines.

Fig. 6 is a section on the line 6—6 of Fig. 2.

Fig. 7 is a longitudinal vertical section 75 through the dust screening device.

Fig. 8 is a longitudinal vertical section of the last thrasher.

Fig. 9 is a section on the line 9—9 of Fig. 8.

Fig. 10 is a longitudinal vertical section 80 of the fiber fan.

Fig. 11 is a section on line 11—11 of Fig. 2.

In the present embodiment of the invention, the apparatus is arranged in three floors, the floors being indicated at A, B 85 and C, of Fig. 1, the stemming apparatus proper being upon floor B, while the receptacles for the leaf, stems and dust are on floor A, which is the lower floor. On the third floor C the blending mechanism is arranged. The said mechanism comprises an endless belt or conveyor 1, which is supported at its ends by rollers 2, one of which is provided with a pulley 3, connected by a belt 4, with a suitable source of power. The rollers 2 are journaled in suitable supports 5 on floor C, and on each side of the belt is arranged a plate 6, the plates extending between the rollers, for retaining the tobacco on the belt, during its travel toward the 90 95 100

mixing device, to be described. The tobacco, which is indicated at 7, is arranged upon the floor, the various grades being in separate piles, as shown, and arranged in lines on opposite sides of the belt, the said piles being usually in the form of cylinders, just as the tobacco comes from the hogshead.

The tobacco is blended on the belt by an operator, who places on the belt the proper proportion of tobacco from each grade, and the belt delivers to the mixing and screening device. The said device comprises a cylinder 8 of perforate material, as for instance, wire mesh, having a frusto-conical imperforate inlet 9. The cylinder is secured to a shaft 10, journalled in suitable bearings in a casing 11 in inclined position, that end of the shaft remote from the belt being extended through the casing for connection with the driving mechanism. Outside the casing the shaft has a bevel gear 12, which meshes with a similar gear 13, rigid with a pulley 14, connected by a belt 15 with a suitable source of power. The mixing and screening cylinder 8—9 is so arranged that the belt 1 may deliver thereto, a chute 16 being arranged at the end of the belt and extending into the portion 9 of the cylinder, over which the tobacco moves, as shown in Fig. 1. The cylinder is connected to the shaft in any suitable manner, as for instance, by spiders, as shown, and the lower end of the cylinder, that is the end remote from the blending belt, delivers through a chute 17 to the first of a plurality of thrashing machines to be later described.

The casing 11 of the mixing and screening devices, is connected with a suitable exhausting device, by means of a pipe 18, having branches 19 connected with the casing near the ends thereof. The blended tobacco passes through the cylinder by gravity, because of the inclined position thereof, and is fed through the chute 17 to the thrashing mechanism. In the cylinder the tobacco is thoroughly mixed and blended, and the dust is removed therefrom.

A plurality of thrashers or disintegrators is provided, each of the cylinder and concave type. The thrashers are arranged in series, or cascade, each delivering to the succeeding device, the mixing device delivering to the first thrasher, and the last delivering to a preceding thrasher. Thus the operation is cyclic, and each thrasher includes screening mechanism for removing from the cycle particles above a selected weight. The screening device of the last thrasher includes a gravity discharge, for particles below another selected weight.

The thrashers in the present instance are four in number, indicated at D, E, F and G, respectively, although it is obvious that the number might be greater or less. All of the 65 thrashers are of the cylinder and concave

type, the density of the spacing of the teeth of cylinder and concave, increasing from the first thrasher to the last. Except for this spacing, the first and intermediate thrashers are alike, and but one will be described. Each is composed of a suitable casing 20, having a hopper extension 21, into which the disintegrated tobacco leaves are delivered from the chute 17. The bottom of the hopper is formed into a concave 22, and the concave is provided with the usual teeth 23, which intermesh with similar teeth 24 on a cylinder 25, journalled co-axially with the concave. Each cylinder has in connection therewith fast and loose pulleys 26, for connection with a suitable source of power, and other pulleys 27 and 28, on the opposite side of the casing from the pulleys 26. Belts 29 and 30 connect the pulleys 27 and 28, with pulleys 31 and 32, respectively, on the shaft 33 of a roller 34, and on the shaft 35 of a fan or blower 36, respectively. The fan 36 is mounted in the upper part of the casing, and the roller 33 is one of a pair, the other indicated at 37.

These rollers have their axes in the same horizontal plane, the roller 33 being at the rear of the casing, while the roller 37 is at the front. Each roller is journalled in an extension from the casing, the said extensions being indicated at 38 and 39, for the respective rollers. A screen 40 in the form of an endless belt is supported by the rollers, and the runs of the screen extend transversely of the casing between the fan and the cylinder. Pairs of guides 41 are provided on the side walls of the casing, the runs moving between the members of the pairs, and it will be evident from the description, that the endless belt 40 forms a moving screen between the fan and the cylinder. The parts just described constitute a screening mechanism, the particles of leaf above a selected weight being carried by the blast from the fan into contact with the screen, which strains such particles from the air blast and delivers them at the rear of the casing, the casing having a delivery opening at this point just below the roller 33, it being understood that the lower run of the belt moves rearwardly.

In order that the leaves will be positively released from the screen when they are outside the casing, a rotary brush 42 is arranged just behind the roller 33, the bristles of the brush contacting with the belt to strip the leaf particles therefrom. This brush is driven by its contact with the belt. Below the delivery opening for the leaf particles in the rear of the casing, a roller 43 is arranged, the said roller bearing against the under side of the roller 33 and the belt 40. The roller 43 is pressed upward resiliently by springs 44 which are arranged between a stop 45 on slidable arms

46, in which the roller is journalled, and a bracket 47 in which the arms are slidale. All of the leaf particles above a selected weight are delivered between the rollers 23—43, to conveying mechanism to be described, while those below this selected weight pass over a deflecting board 48 onto an endless belt or apron 49, which is a conveyor delivering to the succeeding thrasher. 5 Each belt 49 is supported by rollers 50 and 51. The roller 50 is journalled below the deflecting board 48, while the roller 51 is journalled at the top of the hopper 21 of the succeeding thrasher, the arrangement 10 being such that the upper run of the belt delivers to the hopper. A guide board or plate 52 is arranged beneath the upper run of each conveyor 49, and guard strips 53 are arranged at opposite sides of the said 15 upper run, to prevent displacement of the leaves from the run.

Those particles which are above the selected weight, are, as before stated, delivered between the rollers 33 and 43. Such 20 particles fall upon an endless belt 54, which is supported by rollers 55 mounted in suitable support 56. The belts 54 move at right angles to the belts 49, and said belts deliver onto a common picking belt 57, which extends parallel to the belts 49, and is mounted in a manner to be presently described. Those rollers 55 of the conveyors remote from the thrashers are driven by belts 58 which connect pulleys 59 on the rollers with a suitable source of power.

Each of the fans 36 is journalled in a suitable fan casing 60, in the upper part of the casing 20, and each casing has an axial inlet indicated at 61, which may be 40 regulated in regard to the extent of opening by a sliding door 62, the said door 62 being mounted in guides 63 on the casing and having a handle 64 extending above the casing 20. The tangential outlet 65 of each fan communicates by a conduit with a dust collector of suitable construction; the thrasher D by means of a conduit 66, with a collector 67, and the thrashers E and F with a collector 68 by means of conduits 69 and 70. In these collectors the particles of tobacco settle and are delivered through chutes 71 and 72 to a sand screen and riddle device, to be later described, while the dust 50 passes off through flues 71a—72a.

The force of the blast passing upward through the screen 40 is regulated in each thrasher by means of gates or louvers 73, which are arranged transversely of the casing in a damper opening in an inclined partition 74 below and behind the screen 40, the said dampers or louvers being journalled on parallel axes and connected to swing in unison, in the usual manner, thereby to vary the extent of the opening through the partition.

The picking belt 57 before mentioned, is supported by rollers 75 journalled in suitable supports 76, one roller being adjacent the first thrasher, and the other near the last. It will be understood that the thrashers are arranged on the floor B, the blending mechanism and the mixer being on the floor C. The floor A supports the receptacles for the leaf, the stems and the dust, and the picking belt delivers to one of these receptacles in a manner to be presently described.

The last thrasher G is of the Cardwell type, differing from the first and intermediate thrashers, in that it has a plurality of assemblages of cylinder and concave and is provided with a riddling device in connection with the screening mechanism. The said thrasher includes a suitable casing 77, having at the receiving end thereof an opening through which the conveyor 49 of the thrasher F delivers. The delivered tobacco passes down over a grain or deflecting board 78, to the first cylinder-concave assemblage, composed of the cylinder 79 and the concave 80.

The second assemblage 81 comprises a cylinder 81 and a concave 82, and the assemblages are arranged in series or cascade, one delivering to the other. Referring to Fig. 8, it will be seen that the concaves cover less than 90° of the perimeters of the cylinders, being arranged below and in front of the cylinders. Between the delivery end of the concave 80 and the receiving end of the concave 82, a perforate plate or screen 85 is arranged, the said screen being formed on an arc whose center is the center of the cylinder. The tobacco passing between the teeth 83 of the concave and the teeth 84 of the cylinder of the first assemblage, passes over this screen to the second assemblage, where it is in turn engaged by similar teeth 83—84 of the second assemblage. Those particles which are small enough to pass through the openings of the screen, drop down upon the riddle device to be described. The cylinders of the two assemblages are journalled in the walls of the casing, and each is provided outside the casing with pulleys 86 and 87, respectively, said pulleys being connected by a belt 88, so that the cylinders move in unison. At the opposite side of the casing, the cylinder 79 has fast and loose pulleys 89, which are adapted for engagement with a belt 90, connecting the pulleys to a suitable source of power.

The riddling device comprises a box frame 91 which is supported in inclined position, and for swinging movement longitudinally of the casing 77, by means of links 92, the said links being journalled at one end on the frame 91, and at the other secured to the casing 77. The links are resilient, providing for a limited to and fro movement of the frame. The frame is vi-

brated or reciprocated by means of a cam 93, on a cam shaft 94, journalled at the front of the casing. A follower 95 encircles the cam and a link 96 connects the follower with the frame. The cam shaft has a pulley 97, which is connected by a belt 98, with a suitable source of power to rotate said shaft. Three perforate screens or partitions 99, 100 and 101, are arranged transversely of the box frame in vertically spaced relation, and the perforations of the screen decrease in diameter from the upper to the lower screen. The tobacco from the cylinder and concave assemblages is delivered onto the upper screen 99, and a bridge 102 is provided above the screen and extending transversely of the casing, below the cylinder and behind the concave, so that the tobacco passing from the assemblage falls on the bridge and is moved further onto the lower rear end of the screen. The tobacco passing through the screen 85 falls on the screen 99 above and in front of the bridge, and passes down beneath the bridge, so that it is not mixed with the tobacco from the second assemblage, until the tobacco from both assemblages has passed the bridge.

From the screen 99 the disintegrated tobacco leaves are moved rearwardly and gradually overflow the lower end onto a trough 104 supported by the box frame, the screen 99 being arranged below the upper edge of the box frame. The tobacco particles which are small enough to pass through the meshes of screen 99 fall upon the screen 100, and are gradually moved to the rear end thereof, passing through a discharge opening 105 into the trough 104, before mentioned. Within the trough 104, the particles are partly separated into lighter and heavier particles, and all of the particles are eventually fed over the lower side of the trough through a blast of air, which removes those particles of a selected buoyancy from the cycle, and this will include practically all particles which carry leaf lamina. Those particles of stem which are devoid of lamina being much less buoyant, will discharge by gravity, the thrasher having a gravity discharge for this purpose.

Referring to Fig. 8, it will be seen that a fan casing 106 is arranged in the frame of the casing 77 below the rear end of the riddle, and a chute 107 leads upwardly and rearwardly from the fan to a separator casing 108. The chute 107 has a discharge opening 109, just below the rear wall of the trough 104, and those particles which are not sufficiently buoyant to be lifted by the air blast from the fan 110 in the casing, will drop through the discharge 109, and through a chute 111 into a receptacle 112, arranged on floor A. The fan 110 is driven by a belt 113, from a pulley 114 on the cam shaft 94,

the belt connecting the pulley with another pulley 115 on the fan shaft.

Those particles of tobacco which are small enough to pass through the meshes of the screen 100 fall upon the screen 101, and such particles as are too large to pass through the meshes of this screen, are moved toward the rear end of the riddle, eventually reaching a trough 116, which discharges downwardly and laterally from the riddle, as shown more particularly in Fig. 11. Those particles which pass through the meshes of the screen 101 are discharged through a conduit 117 into a dust receptacle 118 on floor A. The blast or discharge from the fan 110 may be regulated by means of a damper 119, which controls the inlet to the fan. Dust is removed from the casing 77, through a port 120. Above the port is a hood 121, connected to a conduit 122, which is a branch of another conduit 123, opening axially of an air pump or compressor 124, which through a discharge conduit 125 supplies air under pressure to the dust collector 67.

The separator casing 108 has a connection 126 with the conduit 123, before mentioned. The chute 107 opens into the under side of the separator and a discharge chute 127 opens from the lower side adjacent to the inlet of the chute 107. Above the outlet end of the chute 107 and the inlet end of chute 127, an arched screen 128 is arranged, the screen separating the casing into two chambers, one of which provides a connection between chutes 107 and 127, and the other of which communicates with conduit 126. A partial vacuum is maintained in the separator casing, which constrains the particles of tobacco of a selected buoyancy to move upward and fall into the chute 127, through which such particles discharge. The dust and the like pass through the screen, and from thence to the compressor 124, being eventually discharged into the dust collector 67. The separator casing 108 has a door 129 at its rear for permitting access thereto, and the screen has transverse baffle plates 130 on its outer face.

Those tobacco particles which have not been already discharged from the cycle, and which are now discharging from the chute 127, are delivered to a conveyor which returns them to the cycle between thrashes E and F. The conveyor comprises an endless belt or apron 131, which is suitably supported by rollers 132, 133, and 134, to maintain the belt with a portion of the upper run thereof inclined upwardly and forwardly from the roller 132, to the roller 133, and horizontally between rollers 133 and 134. The chute 127 delivers through an extension 135 into a box casing 136, which encloses the upper run of the conveyor, and at its forward end the said upper run delivers into a

hopper 137 having a chute 138, delivering to thrasher F. The endless belt 131 is driven from a source of power by a belt 139, which engages a pulley 140 on the roller 134. The lower run of the endless belt 131 is supported near the roller 133 by a guide roller 141. In order to provide proper tension, the roller 132 is journaled in bearing blocks by means of screws 144, threaded through 142, which are slidable in guides in brackets 143 on floor B, and the blocks are adjusted the brackets and rotatably connected with the blocks.

Those particles of tobacco which are small enough to pass through meshes of screen 100 and too large to pass through meshes of screen 101, are delivered by the trough 116 to a conveyor, comprising an endless belt or apron 145, supported by rollers 146 and 147. One of these rollers is arranged below the outlet of the chute or spout 116, and the other is arranged in a position such that the upper run of the conveyor delivers to a fiber fan to be described. The belt 145 is provided with pockets 148 at suitable intervals, which receive and hold the particles of tobacco delivered by the spout and eventually deliver them into the fiber fan. The conveyor 145—148 is driven from the source of power by a belt 149, which engages a pulley 150 on the roller 147.

This fan, shown more particularly in Fig. 10, comprises a suitable supporting frame 151, in which is mounted a vibrating screen 152. The screen is secured transversely of a box frame 153, extending longitudinally of the frame and inclined downwardly toward the front of the apparatus. The frame is supported by resilient links 154, which are pivoted at one end to the riddle frame, and secured at the other to the frame 151. The conveyor 145—148 delivers to a feed-table 155, which delivers the tobacco particles near the upper end of the screen. The screen is vibrated by means of a cam 156 on a cam shaft 157, journaled transversely of the rear end of the frame 151. A follower 158 encircles the cam and a link 159 connects the follower with the box frame 153. It will be obvious that when the shaft is rotated by means of the belt 160, engaging the pulley 161 on the shaft, the box frame will be reciprocated and vibrated to gradually move forwardly the tobacco particles which are too large to pass through the meshes of the screen to and over the lower end thereof. Such particles are delivered into a blast of air from a suitable fan 162, arranged within the fan casing 163 below the box frame. The tangential outlet 164 at the casing front opens into a chute 165, leading from the front end of the frame 151 to a collector casing 166. This chute 165 has a gravity discharge 167, delivering to the upper end of the chute

168, extending through floor B, and discharging into a suitable receptacle 169 on floor A. The discharge or blast of the fan 162 may be regulated by means of a damper door 170, in connection with the casing. A 70 port or opening is provided in the upper wall of the conduit 165, and a perforate screen 171 is arranged across the opening. The port is the inlet end of a conduit 172, 75 communicating with the conduit 123, before mentioned. The tobacco particles from screen 152 discharge over a deflecting board 173, and those particles which pass through the screen are discharged by a spout 174 at the forward or lower end of the 80 screen into a receptacle 174^a, arranged at the side of the fan.

The sand screen and riddling device previously mentioned, to which the chutes 71 and 72 deliver, as shown more particularly 85 in Figs. 6 and 7, includes a suitable supporting frame 175, in which is mounted to reciprocate and vibrate, an open box frame 176. Within the frame three perforate partitions or screens 177, 178 and 179 are 90 arranged, the said screens being spaced apart vertically from each other. The box frame inclines downwardly toward its rear delivery end, and it is supported by resilient links 180, pivoted at their upper ends to 95 the box frame and secured at their lower ends to the frame 175. The box is vibrated by means of a cam 181 on a cam shaft 182, journaled at the front end of the frame. A follower 183 encircles the cam and is 100 connected by a link 184 to the box frame. The shaft is rotated by means of a belt 185, connecting a pulley 186 on the shaft with a source of power.

The screen 177 extends the full length 105 of the box frame, but the screens 178 and 179 stop short of the rear end, so that discharge space is provided between the said rear ends and the rear end of the box frame. A trough 185 is arranged at the rear end 110 of the box frame and the screens 178 and 179 deliver into the trough, the screen 177 delivering over the rear end of the box frame, and the said screen is arranged below the upper edge of the frame. As the box frame is vibrated, the tobacco particles from the upper screen overflow the rear end of the box frame, and drop onto a deflecting plate 186^a which guides them onto a conveyor, comprising an endless belt 187, supported by rollers 188 and 189. The roller 188 is journaled at the outer side of the frame 175 near the floor, while the roller 189 is journaled coaxial with the roller 59, pertaining to the delivery conveyor of 115 thrasher E, and is driven by a belt 190 from the source of power. From the trough 185, before mentioned, the tobacco particles are gradually worked out through a discharge opening in the rear of the box frame, 120 125 130

falling into the deflecting plate 186, where they are mixed with the discharge from screen 177. Those particles which are small enough to pass through all the screens, and which will be stem particles, reach the bottom of the box frame, and are delivered therefrom through a chute 191, falling into a receptacle 192 on floor B. The conveyor 187 has side boards 193, and the conveyors 54, before mentioned, are similarly provided, the boards being indicated at 193^a.

In operation, the tobacco to be blended is arranged on each side of the blending belt, preferably as it comes from the hogshead. 15 With the apparatus in operation, the attendant blends the tobacco from the several heaps in a selected manner on the blending belt, which delivers it to the mixer. Here the mass of leaves is thoroughly mixed, 20 traveling slowly to the delivery end of the mixer, and through the chute 17 to the first thrasher or disintegrator. On this device a portion of lamina is stripped from the stem and those portions having sufficient 25 buoyancy, which will be portions of lamina without stem material, are removed from the cycle by the air blast, being eventually delivered onto the picking belt. The heavier portions pass to thrasher E, where the process is repeated, a full disintegration of the 30 leaf taking place, and a further separation of lamina from the stem. The more buoyant portions are removed from the cycle and the heavier portions pass onto the thrasher F. 35 From thrasher F, those portions of the leaf which have not been removed from the cycle pass to thrasher G, where a more thorough disintegration takes place, and where the riddling device comes into play to assist the 40 air blast in the separation. All the particles capable of being lifted by the air blast have been removed, when the tobacco emerges 45 from thrasher G, those portions constituted by stem only, discharging at the outlet 109, while the lighter stem portions discharge 50 through the conduit 117. All of the leaf portions are blown up through the chute 107 into the separator casing, and eventually reach the conveyor 131, which delivers them 55 to the thrasher F, and again into the cycle. The leaf particles are held in the cycle until all the lamina is removed from the stem portions, so that the stem portions may discharge through outlet 109, or through conduit 117. Each thrasher discharges its quota 60 onto the picking belt. It will be evident from the description, that there is a continuous separation of leaf lamina from the stem, and that only those portions of the leaf incompletely separated are retained in the cycle, when the leaf has been acted upon by 65 thrasher G. Any leaf particles which may reach the dust collectors are separated, and returned to the cycle, by way of the sand screen and riddle, which thoroughly sepa-

rates the particles from foreign matter of every description.

The layout is so designed that the tobacco does not have to be elevated during the time that it is operated upon. From the blending belt the movement is always on the level or downward, until it reaches the floor A, and is separated into lamina and stem. The picking belt delivers at its delivery end into chute 195, which conducts the leaf to a receptacle 196 on floor A. A hood 197 encircles the chute above the receptacle, and a conduit 198 is connected with the hood, to maintain low pressure in the hood, to remove any dust that may remain with the leaf. The particles which reach the collector 196, also discharge into the chute 195, the collector having a spout 199 opening into the chute.

The method is a cyclic method, the apparatus for carrying out the method being constituted in its essentials by mechanism for breaking up the leaf and for separating the lamina from the stem particles, together with means for constraining the leaves to pass in cycle through said mechanism, and other means to separately remove leaf lamina and stem particles. The cycle includes thrashers F and G, the tobacco leaves being constrained to pass in cycle through these thrashers, with continuous and separate removal of buoyant particles and heavier stem particles. It is obvious that the cycle might include all of the thrashers, if desired, the leaves being returned to the cycle in advance of thrasher D. This, however, would slow the operation to some extent, cutting down the capacity of thrashers D and E by the amount of tobacco returned into the cycle from thrasher G. At thrasher F a considerable part of the fed tobacco has been already removed, so that that portion of the tobacco returned to the cycle does not overburden thrasher F, and thrashers D and E may operate to their capacity.

While in the present arrangement the layout is shown on three floors, the tobacco could be handled in the same manner on one floor, and this lay-out in some instances may be preferable. The blending mechanism may be dispensed with if desired, the tobacco being fed directly into the screening device or into the first thrasher as may be desired.

In some instances, and with some kinds of tobacco, the thrashers D, E, F, of the first mentioned type, may be used alone, with or without the fiber fan, and the thrashers D, E, F, and G, might be used together without the fiber fan. In some instances it might even be advisable to make all of the thrashers of the G, type.

As the leaves pass through the thrashers, the stem portions are broken into small pieces and all of the lamina is thoroughly

cleaned or removed from the stem portions. Practically every particle of the leaf lamina is recovered even those particles which are buoyant enough to be carried away by the air current to the dust collectors. The finer particles may be mixed with the coarse particles or they may be separately collected as desired.

We claim:

1. The method of stripping tobacco, which comprises subjecting the leaves to a succession of disintegrating operations, winnowing out the buoyant particles between successive operations and discharging heavier particles by gravity at regular intervals after a selected number of operations.

2. The method of stripping tobacco, which comprises subjecting the leaves to a succession of disintegrating operations, winnowing out the buoyant particles between successive operations and discharging heavier particles by gravity after the succession of operations, and subjecting the remaining portions of the leaves to a succession of alternating, disintegrating and screening operations.

3. The method of stripping tobacco, which comprises subjecting the leaves to the action of a succession of thrashers, winnowing out the lighter particles between successive thrashers, discharging heavier particles by gravity after the succession of thrashing operations, and mixing the remaining portions of the leaves with the tobacco passing through the thrashers.

4. The method of blending and stripping tobacco, which comprises mixing the blended tobacco in the presence of an air blast thereby to remove the dust and the like, subjecting the leaves to the action of a succession of thrashers, winnowing out the lighter particles between successive thrashers, discharging heavier particles by gravity after the succession of thrashing operations, and mixing the remaining portions of the leaves with the tobacco passing through the thrashers.

5. The method of stripping tobacco, which comprises subjecting the leaves to the action of a succession of thrashers while retaining all of the leaves in the circulation except the buoyant particles, screening the tobacco after it has passed all of the thrashers to remove the stem particles, and returning the remainder of the leaves to the tobacco passing through the thrashers.

6. The method of stripping tobacco, which comprises passing the leaves through a succession of sets of intermeshing teeth having relative movement in opposite directions, and gradual increasing density of spacing, subjecting the leaves between the successive sets to the action of a regulated blast of air to remove the lighter particles, screening the leaves from the last set to re-

move heavier particles and returning the remainder to the tobacco passing through the sets.

7. Tobacco stemming apparatus, comprising a plurality of sets of intermeshing teeth having relative movement in opposite directions to break the leaves including the stems into fragments, the teeth of the sets gradually increasing in density of spacing, tobacco feeding means leading from one set to another and means in connection with each set for removing the lighter particles, said means at the last set having a gravity discharge for stem particles.

8. Tobacco stemming apparatus, comprising a plurality of sets of intermeshing teeth having relative movement in opposite directions to break the leaves including the stems into fragments, the teeth of the sets gradually increasing in density of spacing, tobacco feeding means leading from one set to another means in connection with each set for removing the lighter particles, said means at the last set having a gravity discharge for stem particles, and means for delivering the remainder of the leaves from the last set to a preceding set.

9. Tobacco stemming apparatus, comprising a plurality of thrashers for breaking the leaves including the stems into fragments, delivering one to the other, the last delivering to a preceding thrasher, means in connection with each thrasher for removing the lighter particles, the last of said means having a gravity discharge for stem particles.

10. Tobacco stemming apparatus, comprising a plurality of thrashers for breaking the leaves including the stems into fragments, delivering one to the other, the last delivering to a preceding thrasher, screen mechanism in connection with each thrasher, each mechanism including an air blast for removing lighter particles, the last of said mechanism having a gravity discharge for particles below a selected size and above a selected weight.

11. Tobacco stemming apparatus, comprising a plurality of thrashers for breaking the leaves including the stems into fragments, delivering one to the other, the last delivering to a preceding thrasher, screen mechanism in connection with each thrasher, each mechanism including an air blast for removing lighter particles, the last of said mechanism having a gravity discharge for particles below a selected size and above a selected weight, and a mixing device mixing the leaves delivering to the first thrasher.

12. Tobacco stemming apparatus, comprising a plurality of thrashers for breaking the leaves including the stems into fragments, delivering one to the other, the last delivering to a preceding thrasher, screen mechanism in connection with each thrasher, each

mechanism including an air blast for removing lighter particles, the last of said mechanisms having a gravity discharge for particles below a selected size and above a selected weight, blending mechanism, and a mixing device mixing the leaves to which the blending mechanism delivers, said device delivering to the first of the thrashers.

13. Tobacco stemming apparatus, comprising a plurality of thrashers for breaking the leaves including the stems into fragments, delivering one to the other, the last delivering to a preceding thrasher, screen mechanism in connection with each thrasher, each mechanism including an air blast for removing lighter particles, the last of said mechanisms having a gravity discharge for particles below a selected size and above a selected weight, and including superposed riddles decreasing in mesh from above downward.

14. Tobacco stemming apparatus, comprising a plurality of thrashers for breaking the leaves including the stems into fragments, delivering one to the other, the last delivering to a preceding thrasher, screen mechanism in connection with each thrasher, each mechanism including an air blast for removing lighter particles, the last of said mechanisms having a gravity discharge for particles below a selected size and above a selected weight, said thrashers being of the cylinder and concave type and each having a continuously moving screen cooperating with the air blast for straining the particles therefrom.

15. Tobacco stemming apparatus, comprising a plurality of thrashers for breaking the leaves including the stems into fragments, delivering one to the other, the last delivering to a preceding thrasher, screen mechanism in connection with each thrasher, each mechanism including an air blast for removing lighter particles, the last of said mechanisms having a gravity discharge for particles below a selected size and above a selected weight, a dust collector in connection with each thrasher, and means to maintain partial vacuum in each thrasher.

16. In tobacco stemming apparatus, mechanism constructed to break up tobacco leaves including their stems and to separate lamina from the stem particles, means to constrain the leaves to pass in cycle through said mechanism, and means interposed in the cycle for separately removing leaf lamina substantially free from stem particles, and stem particles substantially free from leaf lamina.

17. In tobacco stemming apparatus, mechanism constructed to break up tobacco leaves including their stems and to separate lamina from the stem particles, means to constrain the leaves to pass in cycle through said mechanism, means interposed in the cycle for separately removing leaf lamina sub-

stantially free from stem particles, and stem particles substantially free from leaf lamina, and blending and mixing mechanism for the leaves delivering to the cycle.

18. In tobacco stemming apparatus, mechanism constructed to break up tobacco leaves including their stems and to separate lamina from the stem particles, means to constrain the leaves to pass in cycle through said mechanism, means interposed in the cycle for separately removing leaf lamina substantially free from stem particles, and stem particles from leaf lamina, and blending and mixing mechanism for the leaves delivering to the cycle, said mechanism including a rotary cylindrical screen inclined downwardly from its inlet end, to which the several grades of tobacco are delivered.

19. In tobacco stemming apparatus, mechanism constructed to break up tobacco leaves including their stems and to separate lamina from the stem particles, means to constrain the leaves to pass in cycle through said mechanism, and means interposed in the cycle for separately removing leaf lamina substantially free from stem particles, and stem particles substantially free from leaf lamina, said last named means including an air blast and a perforate screen moving continuously in one direction against which leaf lamina particles are blown.

20. In tobacco stemming apparatus, mechanism constructed to break up tobacco leaves including their stems and to separate lamina from the stem particles, means to constrain the leaves to pass in cycle through said mechanism, means interposed in the cycle for separately removing leaf lamina substantially free from stem particles, and stem particles substantially free from leaf lamina, said last named means including an air blast and a perforate screen moving continuously in one direction against which leaf lamina particles are blown, and a succession of vibrating screens of decreasing mesh.

21. In tobacco stemming apparatus, mechanism constructed to break up tobacco leaves including their stems and to separate lamina from the stem particles, means to constrain the leaves to pass in cycle through said mechanism, and means interposed in the cycle for separately removing leaf lamina substantially free from stem particles, and stem particles substantially free from leaf lamina, said breaking up and separating mechanism including a plurality of sets of intermeshing teeth having relative movement in opposite directions.

22. In tobacco stemming apparatus, mechanism constructed to break up tobacco leaves including their stems and to separate lamina from the stem particles, means to constrain the leaves to pass in cycle through said mechanism, and means interposed in the cycle for separately removing leaf lamina

substantially free from stem particles, and stem particles substantially free from leaf lamina, said breaking and separating mechanism including a plurality of thrashers of cylinder-concave type.

23. In tobacco stemming apparatus, a plurality of thrashers to break up the leaves including the stems, a plurality of mechanisms for separating and removing buoyant leaf particles, means for constraining tobacco leaves to pass in alternation through the thrashers and the separating mechanisms, and means to return the remaining portions of the leaves into the circulation at a point where the quantity returning is not greater than that which has been removed.

24. Tobacco stemming apparatus, comprising a plurality of toothed cylinder and concave assemblages to break up the tobacco leaves including the stems, means to pass the tobacco leaves through the assemblages in succession, means to separately remove the lighter and the heavier particles, and means to return the remaining leaves to the circulation between the first and last assemblage.

25. Tobacco stemming apparatus, comprising a plurality of toothed cylinder and concave assemblages to break up the tobacco leaves including the stems, means to pass the tobacco leaves through the assemblages in succession, means between the adjacent assemblages for separating the light particles, gravity controlled means at the end of the succession for removing heavier particles, and means to return the remainder of the leaves to the circulation between the first and last assemblage.

26. Tobacco stemming apparatus, comprising a plurality of toothed cylinder and concave assemblages to break up the tobacco leaves including the stems, means to pass the tobacco leaves through the assemblages in succession, means between the adjacent assemblages for separating the light particles, gravity controlled means at the end of the succession for removing heavier particles, means to return the remainder of the leaves to the circulation between the first and last assemblage, and means to blend and mix the leaves prior to their entrance into the circulation.

27. Tobacco stemming apparatus, comprising means to move tobacco leaves in a continuous cycle, including a plurality of independent mechanisms for operating upon the same to break the leaves including the stems and separate the lamina from the stems, and other mechanism to separately remove the lighter and the heavier particles.

28. Tobacco stemming apparatus, comprising means to move tobacco leaves in a continuous cycle, including a plurality of independent mechanisms for operating upon

the same to break the leaves including the stems and separate the lamina from the stems, means adjacent the mechanisms to remove the lighter particles, and gravity controlled means in connection with the last of said mechanisms for removing the heavier particles.

29. Tobacco stemming apparatus, comprising means to move tobacco leaves over a path, the last portion of which is cyclic, and mechanisms through which the leaves are passed for breaking up the leaves including the stems and separating the lamina from the stem, sundry of said mechanisms being in the cyclic portion of the travel of the leaves, and means in connection with said mechanisms to separately remove the lighter particles and the heavier particles.

30. Tobacco stemming apparatus, comprising means to move tobacco leaves over a path, the last portion of which is cyclic, and mechanisms through which the leaves are passed for breaking up the leaves including the stems and separating the lamina from the stem, sundry of said mechanisms being in the cyclic portion of the travel of the leaves, and means in connection with said mechanisms to separately remove the lighter particles and the heavier particles, said mechanisms being of the cylinder and concave thrasher type.

31. A tobacco stemming plant layout comprising a plurality of thrashers arranged in series on an intermediate floor for breaking up the leaves including the stems, mechanism for blending tobacco leaves on an upper floor, a chute receiving the leaves from the blending mechanism and delivering them to the first of the thrashers, receptacles for the product on a lower floor, and chutes for conducting the lamina, the stems and the dust to the receptacles.

32. A tobacco stemming plant layout comprising a plurality of thrashers arranged in series on an intermediate floor for breaking up the leaves including the stems, mechanism for blending tobacco leaves on an upper floor, a chute receiving the leaves from the blending mechanism and delivering them to the first of the thrashers, receptacles for the product on a lower floor, chutes for conducting the lamina, the stems and the dust to the receptacles, dust collectors on the upper floors, and connections between the mechanisms on the upper and intermediate floors and the dust collectors.

33. A tobacco stemming plant layout comprising a plurality of thrashers in series on an intermediate floor for breaking tobacco leaves including the stems, mechanism for blending tobacco leaves on an upper floor, receptacles for the finished product on a lower floor, and means to transport the leaves from the blending mechanism to and

through the thrashers, with the travel of the leaves through the last thrashers cyclic.

34. A tobacco stemming plant layout comprising blending mechanism, a plurality of thrashers in series to the first of which the blending mechanism delivers, means to transport the leaves from the blending mechanism to and through the thrashers

with the travel of the leaves through the last thrashers cyclic, and receptacles for the finished product at suitable intervals.

Signed at Richmond, in the county of Henrico and State of Virginia this 25th day of Sept., A. D. 1924.
